O. JOHNSON,
MECHANICAL MOVEMENT FOR WEAVING MACHINES,
APPLICATION FILED MAR. 28, 1917.

1,295,756.

Patented Feb. 25, 1919.

UNITED STATES PATENT OFFICE.

OLOF JOHNSON, OF NORTHLVILLE, NEW YORK.

MECHANICAL MOVEMENT FOR WEAVING-MACHINES.

1,295,756.

Specification of Letters Patent. Patented Feb. 25, 1919.

Application filed March 28, 1917. Serial No. 157,894.

To all whom it may concern:

Be it known that I, OLOF JOHNSON, a citizen of the United States, and a resident of Northville, county of Fulton, State of New York, have invented certain new and useful Improvements in Mechanical Movements for Weaving-Machines, of which the following is a specification.

My invention relates to weaving machines, and is particularly addressed to providing a differential motion so as to move the guide bars when, during the operation of the machine, such movement is necessary.

In the operation of weaving machines, it is necessary that the movement of the guide bars be very rapid, and for this purpose, I have provided a differential movement which is simpler, more positive and less liable to breakage than movements heretofore used in this class of machines.

In the drawings, I have for simplicity shown only that part of a weaving machine to which my invention relates.

Figure 1 is a side view of a portion of the machine showing my invention;

Fig. 2 is an end view of Fig. 1;

Fig. 3 is a diagram showing the relative motion of the power shaft and driven shaft; and

Fig. 4 is a detail of the guide bar operating means.

In the drawings, 1 is the frame or support of a weaving machine. 2 is a shaft which I will call the power-shaft, it being driven from any suitable source of power. Upon one end of this shaft is fixedly secured a disk 3 by set screws 4. 5 is a shaft to be driven with a variable motion. This shaft 5 is mounted in bearings 6 in the frame 1 and is, as will be noticed, parallel to shaft 2, but offset from the center thereof. 7 is an arm integral with the shaft 5, but offset therefrom, in which is mounted a bolt or pivot 8. In the disk 3 is a bolt or pivot 9. 10 is a link loosely mounted on pivots or bolts 8 and 9. As shaft 2 rotates, the disk 3 fastened thereto, rotates with it and through bolt or pivot 9, link 10 and bolt or pivot 8, rotary motion is transmitted to the shaft 2 and owing to the shaft 5 being offset from shaft 2, a differential rotary motion is thereby imparted to shaft 5, as is shown in diagram 3. In this diagram the small letters represent the bolt or pivot 9 in the disk 3, and the capital letters represent the bolt or pivot 8 in the offset 7 of the shaft 5. It

will be noted that while the pivot 9 in the disk 3 on power shaft 2 is rotating from the point *a* to the point *b*, the pivot 8 in the arm 7 of shaft 5 rotates from *A* to *B*. While the pivot 9 in the disk 3 on shaft 2 rotates from the point *b* to the point *c*, the pivot 8 in the arm 7 of shaft 5 rotates from the point *B* to the point *C*. While the pivot 9 in the disk 3 on shaft 2 rotates from the point *c* to the point *d*, the shaft 5 rotates from the point *C* to the point *D*, which, it will be noted, is a much shorter distance than from the preceding point *B* to *C*. While the pivot 9 in the disk 3 on shaft 2 rotates from the point *d* to the point *e*, the pivot 8 in the arm 7 of shaft 5 rotates from *D* to *E*. While the pivot 9 in the disk 3 on shaft 2 rotates from the point *e* to the point *f*, the pivot 8 in the arm 7 of the shaft 5 rotates from *E* to *F*. As it will be seen from this diagram, the rotation of the shaft 2, although positive and regular, transmits the differential motion to the shaft 5 by means of the link 10. Keyed or otherwise secured to the shaft 5 is a worm-gear 11 which meshes with gear 12 secured to shaft 13, so that the differential rotary motion of shaft 5 is imparted to shaft 13 by worm 11 which meshes with gear-wheel 12. Fixedly secured to shaft 13 are index or stud-wheels 14 and 15, which, have mounted in their peripheries the movable studs 18 adapted to be moved and held in any desired position by the bolts 19. The position of these studs, which varies the configuration of the periphery of the stud-wheels 14, 15, determines when the guide bar is to be moved, the motion of the guide bar being caused by the roller 20 passing from one elevation to another of the studs 18.

In Fig. 4, I have shown a view of a small portion of the apparatus from the opposite side of Fig. 1 in which I have shown the rocking arm 16, in the lower end of which is loosely mounted the roller 20, kept normally in contact with the studs 18 by the spring 22. This rocking lever 16 is pivoted in the frame 1 on the shaft or pivot 25, and has at its upper end a pin 24 which connects with the arm or link 23 of the guide bar so that as the roller 20 passes from one elevation to another of the studs, the spring 22, keeping the roller 20 normally pressed against the studs 18, rocks the lever 16, and that rocking motion is imparted to the link 23 of the guide bar so as to move the guide bar in either direction, depending upon

whether the roller 20 has passed to a higher elevation or a lower elevation.

The arrangement of the differential motion imparted by my invention is such that the passing of the roller 20 from one elevation to another of the studs is so arranged that it takes place when the rotation of shaft 13 is most rapid, it being necessary that the movement of the guide bars be as rapid 10 as possible.

While I have shown my invention as applied to a weaving machine, the differential motion may, of course, be used wherever desirable and in any apparatus where a differential motion is necessary.

Having described my invention, what I claim as new and desire to secure by Letters Patent is:

1. In a mechanical movement for weaving machines, means for moving the guide-bars, consisting of a rocking lever, a power-shaft, a driven-shaft, offset from the said power-shaft, an arm fixed to said driven shaft, means connecting said arm and said power-shaft and means for transforming the variable rotary motion of said driven-shaft so as to operate said lever.

2. In a mechanical movement for weaving machines, a power-shaft, a driven-shaft

offset from the center of said power-shaft, 30 means connecting said driven-shaft and said power-shaft so as to impart a variable motion to said driven-shaft, a worm-gear rotating with said driven-shaft, a gear meshing with and operated by said worm-gear, a 35 shaft operated by said last-mentioned gear, a disk fixedly mounted on said last-mentioned shaft, said disk having an irregular periphery, a rocking lever adapted to be rocked by the said irregular periphery and 40 means connecting said lever with a guide bar to operate same.

3. In a differential movement for weaving machines, a power-shaft, a driven shaft offset from the center of said power-shaft, means 45 connecting said driven-shaft and said power-shaft so as to impart a variable movement to said driven shaft, a disk provided with means for changing the configuration of its periphery, means for transmitting the motion of said driven-shaft to said disk and means in contact with the periphery of said disk to transmit motion therefrom to a guide bar.

In testimony whereof I have signed my 55 name to this specification.

OLOF JOHNSON.
